(57) CLAIM

The ornamental design for a footie garment patch as shown and described.

DESCRIPTION

FIG. 1 is a front view of a footie garment patch showing my new design;

FIG. 2 is a rear view of the footie garment patch;

FIG. 3 is a right side view of the footie garment patch;

FIG. 4 is a left side view of the footie garment patch;

FIG. 5 is a top view of the footie garment patch;

FIG. 6 is a bottom view of the footie garment patch;

FIG. 7 is a top front side perspective view of the footie garment patch in an alternative position; and,

FIG. 8 is a front bottom side perspective view of the footie garment patch in use.

The broken lines are illustrative of environmental structure forming no part of the claimed design.

1 Claim, 6 Drawing Sheets
